UNITED STATES PATENT OFFICE.

GEORGE E. FROST, OF SHEBOYGAN, WISCONSIN, ASSIGNOR TO THE FROST VENEER SEATING COMPANY, (LIMITED,) OF SAME PLACE.

PATTERN.

SPECIFICATION forming part of Letters Patent No. 373,451, dated November 22, 1887.

Application filed March 12, 1887. Serial No. 230,636. (No model.)

To all whom it may concern:

Be it known that I, GEORGE E. FROST, of Sheboygan, county of Sheboygan, Wisconsin, have invented certain new and useful Im-
5 provements in Patterns, of which the follow-
ing is a specification.

My invention relates to that class of pat-
terns which are used by laying them upon the
object and cutting around the pattern; and it
10 consists in the particulars hereinafter set forth.
Heretofore patterns for this purpose have been
made of pasteboard and bound around the
edge with brass to prevent their being bent or
broken, or cut by the knife when in use.

15 These patterns are expensive, and the brass
edge tends to dull the knife when in use, be-
sides which, as the edge is bound with brass,
the central part of the patterns will not lie
smoothly and evenly upon the material to be
20 cut, but there will always be more or less of
a space between the pattern and the material,
which will allow the material to pucker and
wrinkle, and thus get out of shape. To avoid
these objections, I use material formed of two
25 or more veneers or laminæ of wood, with the
grain crossing and glued together, which I
have found by experiment to be particularly
suitable for this purpose when the patterns
are constructed as I shall hereinafter explain.

30 In the drawings I have shown patterns for
parts of a shoe, Figures 1, 2, and 3 being plan
views of various parts, and Fig. 4 being an
edge view showing the beveled edge at *a a*.

I make my patterns by first cutting them
35 out of flat pieces of three-ply veneer, thus giving
them the desired outline. The edges must
be smooth, so as not to catch the knife when
in use, and I find it preferable to give them
the rounded or beveled form shown in Fig. 4,
40 which I find will not catch the knife. Besides,
the nature of the material is such that instead
of blunting and dulling the knife in use, it acts to
whet and keep the knife-blade sharp; and this
feature may be still further availed of by oil-
45 ing the edges of the pattern, as indicated by
the shaded lines in the drawings, which will

cause it to not only whet the blade better, but
also to polish and present a smoother surface
to the blade. Again, the pattern being flat,
without any raised edge, its whole surface will 50
lie evenly and smoothly upon the material to
be cut, and allow no room for it to wrinkle or
pucker or slip out of shape, as is the case in
using the brass-bound patterns; and while my
improved pattern is light and very durable, 55
it is very much cheaper to make than the old
style, is easily packed without fear of injury,
and will be found by the trade to be a very
desirable article.

Laminae of wood glued together with the 50
grain crossing are peculiarly well adapted as
material for cutting out patterns, as they lie
perfectly flat and never twist. The edges of
the exterior laminæ may be beveled, and they
will still support and be supported by the 55
central lamina on all sides of the pattern.
The edges are uniformly hard and smooth all
round, and the pattern is not liable to split
away or break off at sharp corners. The pat-
terns cost less than brass-bound patterns, and 60
the beveled edges clear the knife, so that its
edge is not blunted and the pattern is not cut.
A brass-bound pattern cannot be given be-
veled edges, except at very great cost.

Having thus described my invention, what I 75
claim, and desire to secure by Letters Patent
of the United States, is—

As a new article of manufacture, a cutting-
out pattern formed of three laminæ of wood
glued together with the grain crossing, the 80
edges of the said laminæ being smoothly pol-
ished for the knife to bear against, and the
outer laminæ beveled to clear the knife-edge
and still support the center lamina, thus pro-
ducing a hard grainless edge all round the 85
pattern, substantially as and for the purpose
set forth.

GEORGE E. FROST.
